CLAIM

The ornamental design for a toy figure as shown and described.

DESCRIPTION

FIG. 1 is a front elevational view of a toy figure, showing the new design;

FIG. 2 is a rear elevational view thereof;

FIG. 3 is a left-side elevational view thereof;

FIG. 4 is a right-side elevational view thereof;

FIG. 5 is a top plan view thereof;

FIG. 6 is a bottom plan view thereof;

FIG. 7 is a front, right-side, top perspective view thereof;

FIG. 8 is a rear, left-side, top perspective view thereof;

FIG. 9 is a front, right-side, bottom perspective view thereof;

FIG. 10 is a front, left-side, top perspective view of an alternate configuration thereof; and,

FIG. 11 is a front, left-side, top perspective view of an alternate configuration thereof.

The broken line showing of the toy figure is for the purpose of illustrating portions of the article that form no part of the claimed design.
